UNITED STATES PATENT OFFICE

137,479

DESIGN FOR A COUPON SORTING AND DISPENSING RECEPTACLE

James H. Martin, Chicago, Ill.

Application May 24, 1943, Serial No. 110,272

Term of patent 3½ years

(Cl. 52—2)

To all whom it may concern:

Be it known that I, James H. Martin, a citizen of the United States, residing in the city of Chicago, county of Cook, and State of Illinois, have invented a new, original, and ornamental Design for a Coupon Sorting and Dispensing Receptacle, of which the following is a specification, reference being had to the accompanying drawing, forming a part thereof.

In the drawing:

Fig. 1 is a perspective view of a coupon sorting and dispensing receptacle embodying my new design.

Fig. 2 is a perspective view of the same with the cover open.

The right hand end wall is similar to the left hand end wall which is shown in the drawing. The back wall is plain.

I claim:

The ornamental design for a coupon sorting and dispensing receptacle, as shown and described.

JAMES H. MARTIN.
